UNITED STATES PATENT OFFICE

JOSEPH ANTONIO GUARINO, OF WESTERLY, RHODE ISLAND

STOCKING PROTECTOR

Application filed January 28, 1929. Serial No. 335,593.

My present invention has reference to ladies' stocking protectors, the object being the provision of an article of this character which may be easily, quickly and snugly sustained upon the leg of the user and which has at its upper end a fold that provides a cuff and likewise affords a receptacle for a pocketbook and for other articles.

A still further object is the provision of an article of this character which is preferably constructed of rubber or rubberized material and which wholly covers the leg from a suitable distance above the foot portion of the user and which, when not in use, may be folded into a small compact bundle and still serve as a container for pocketbooks, money and other valuables.

To the attainment of the foregoing the invention consists in the improvement hereinafter described and definitely claimed.

In the drawings:

Figure 1 is a side elevation of the improvement in applied position.

Figure 2 is a transverse sectional view showing the improvement folded.

Figure 3 is a sectional view approximately on the line 3-3 of Figure 1.

Figure 4 is a sectional view on the line 4-4 of Figure 1.

The protector is in the nature of a legging and is preferably constructed of rubberized material which is sufficiently elastic to snugly fit the leg of the wearer. The protector 1 has an instep portion 2 and a heel portion 3, and between these portions there are straps 4 that are connected by suitable fastening means. At a suitable distance above the lower portion of the legging, the same from the outer side thereof is slitted longitudinally for a suitable distance to afford the convenient application of the improvement on the wearer. Projecting from the slitted portion there is a flap 5 and fastening means 6 connect the lapping portion of the flap to the body of the legging.

The legging, adjacent to the top thereof, is integrally formed with an upwardly extending cuff that affords a pocket 7. The upper edge of the legging is designed to be folded over the cuff or pocket to fully close

said pocket. The pocket is designed to receive therein a purse 8, and likewise to receive therein an elastic band 10 when the legging is folded upon itself as disclosed by Figure 2 of the drawings. The elastic band 10 is received in the pocket 7 when not thus required for use.

The folded upper end 12 of the legging is designed to be engaged by a fastening element 11 which is attached to the cuff or pocket 7 and this element 11 is designed to likewise engage with the elastic band 10 when the legging is folded as disclosed by Figure 2 of the drawings.

Having described the invention, I claim:

A lady's stocking protector of elastic material having a cuff adjacent to the upper end thereof which affords a pocket for the legging, the said upper end of the legging designed to be folded over the pocket, fastening means between the pocket and the folded portion of the legging and said fastening means also designed to engage with a band which is arranged around the folded portion of the legging.

In testimony whereof I affix my signature.

JOSEPH ANTONIO GUARINO.
